UNITED STATES PATENT OFFICE

160,731

ARTICLE SUPPORTING FIGURINE

Eoina Nudelman, Chicago, Ill.

Application April 23, 1949, Serial No. 2,207

Term of patent 14 years

(Cl. D29—23)

To all whom it may concern:

Be it known that I, Eoina Nudelman, a citizen of the Republic of France, residing at Chicago, in the county of Cook and State of Illinois, have invented a new, original, and ornamental Design for an Article Supporting Figurine, of which the following is a specification, reference being had to the accompanying drawings, forming part hereof.

In the drawings:

Fig. 1 is a front perspective view of an article supporting figurine, showing my new design.

Fig. 2 is a rear perspective view thereof. The dotted line disclosure of the fork and spoon is included for illustrative purposes only.

I claim:

The ornamental design for an article supporting figurine, as shown and described.

EOINA NUDELMAN.
